CLAIM

The ornamental design for a display screen or portion thereof with a graphical user interface for displaying cell

culture process steps and measurements of an associated bioreactor device, as shown and described.

DESCRIPTION

FIG. 1 is a front view of an example embodiment of a display screen or portion thereof with a graphical user interface for displaying cell culture process steps and measurements of an associated bioreactor device in accordance with the claimed design;

FIG. 2 is a front view of another example embodiment of a display screen or portion thereof with a graphical user interface for displaying cell culture process steps and measurements of an associated bioreactor device in accordance with the claimed design;

FIG. 3 is a front view of another example embodiment of a display screen or portion thereof with a graphical user interface for displaying cell culture process steps and measurements of an associated bioreactor device in accordance with the claimed design;

FIG. 4 is a front view of another example embodiment of a display screen or portion thereof with a graphical user interface for displaying cell culture process steps and measurements of an associated bioreactor device in accordance with the claimed design;

FIG. 5 is a front view of another example embodiment of a display screen or portion thereof with a graphical user interface for displaying cell culture process steps and measurements of an associated bioreactor device in accordance with the claimed design; and,

FIG. 6 is a front view of another example embodiment of a display screen or portion thereof with a graphical user interface for displaying cell culture process steps and measurements of an associated bioreactor device in accordance with the claimed design.

The outermost broken lines in the figures show a display screen or portion thereof, and form no part of the claimed design.

The remaining broken lines in the figures show portions of the graphical user interface, and form no part of the claimed design.
